RADIO MONITORING SYSTEM

Albert Preisman, Flushing, N. Y., assignor to
 Federal Telephone and Radio Corporation,
 Newark, N. J., a corporation of Delaware

Application May 7, 1943, Serial No. 485,970

6 Claims. (Cl. 250—20)

1

The present invention relates to radio monitoring systems and more particularly to radio systems for intercepting radio transmission from particular stations.

Numerous systems have been proposed wherein a receiving station is tuned over a band of frequencies in order to locate a particular transmission station as to frequency of broadcast or transmission. In some of these proposed systems a receiver is provided which is continuously tuned over particular frequency bands so that communications may be detected even though the frequency of transmission is periodically changed.

It is an object of the present invention to provide a radio receiver in which the tuning is continuously varied except for regular periods of fixed tuning.

It is a further object of the invention to provide a scanning condenser which will provide intervals of fixed tuning alternately with periods of variable tuning.

It is a still further object of the invention to provide a circuit for controlling the scanning of an oscilloscope indicator simultaneously with the variation in tuning of a scanning receiver.

According to a feature of my invention, a system is provided wherein a condenser is charged and discharged at particular intervals through the medium of a mechanical switching arrangement to produce a desired wave pattern for controlling the scanning of a cathode-ray oscilloscope. At the same time this mechanical control of the cathode-ray scanning circuit may be operated in timed relationship with the adjustment of mechanically variable tuning elements in a receiver so that the scanning of the beam of the oscilloscope will coincide with the changes in tuning of the receiver. Since the invention proposes the use of a receiver having intervals of fixed tuning as well as intervals of variable tuning, the mechanical control of the cathode-ray scanning circuit is arranged so as to show this fixed tuning interval as a separate trace on the screen of the oscilloscope, and of sufficient enlargement so that the single frequency received during this interval may be readily inspected. Furthermore, the invention provides means for separating this single frequency trace from the frequency band shown by the intervals of variable tuning, and for removing this single frequency trace to a separate portion of the screen. Other means are provided for selecting from the entire wave band pictured the single frequency to be traced, and also for blanking the beam of the tube during the scanning return periods. Thus any frequency seen on the

2

screen in the usual manner may be separated from the other frequencies, transferred to a separate portion of the screen, and then swept across the screen to permit close inspection of its characteristics.

A further object of the invention is the provision of a control circuit for producing the particular wave pattern required for scanning the cathode-ray oscilloscope when applicant's novel type of scanning condenser is employed.

A better understanding of the invention and the objects and features thereof may be had from the particular description made with reference to the accompanying drawings, in which:

Fig. 1 is a schematic circuit diagram illustrating a radio system incorporating the features of my invention;

Fig. 2 is a set of curves used to explain the operation of the system illustrated in Fig. 1;

Fig. 3 is a view of the scanning condenser used in the circuit of Fig. 1;

Figs. 4 and 5 are views of a cathode-ray oscilloscope screen illustrating types of indications which may be shown thereon.

In Fig. 1 is shown a receiver 6 having two tuning condensers C_1 and C_2 connected in parallel. The receiving circuit incorporating these condensers may be of any suitable type. C_2 is a manually controlled condenser used to pre-select a desired wave band. C_1 is a motor driven scanning condenser of a type hereinafter to be described, and is used periodically to tune the receiver over the wave band selected by C_2 .

A motor 7 is provided to drive the scanning condenser C_1 . Synchronously controlled by the same motor 7 is a rectangular wave generator 8, which feeds pulses to three wave spacers and shapers 9, 10 and 11. The outputs of wave spacers and shapers 9 and 10 are fed to the grids of triodes V_2 and V_1 respectively. The output of wave spacer and shaper 11 is amplified at 12 and then applied to the grid of a cathode-ray oscilloscope 14.

A rotating switch S_1 is controlled synchronously with the condenser C_1 and wave generator 8 by the motor 7 as indicated in Fig. 1. A condenser C_3 in parallel with S_1 is alternately charged and discharged by rotation of S_1 and the output applied to the horizontal deflection plates of the oscilloscope 14.

The condenser C_1 of Fig. 1 is designed as shown in Fig. 3. The rotor 15 has a portion cut-out as at ABC. As the rotor rotates, the capacity increases until cut-out ABC enters the stator 16. Over arc AC very little, if any, change in capacity should occur. If desired, an additional segment

DE may be employed as shown, so that the capacity can be made to remain perfectly constant (or even decrease, depending on the design of the segment) over arc AC, since DE can be made to compensate for the fringing effect of sides AB and BC. The variation in tuning with time is shown in Fig. 2 (D). While the cut-out ABC is entering the stator 16 the frequency responsiveness of the receiver 6 is constant, MN of Fig. 2 (D). Further rotation increases the frequency to which the receiver is receptive from N to P, at which time the rotor 15 except for the segment DE is entirely within the stator 16. As the rotor leaves the stator the curve reverses, PQRZ, with another constant period QR. It will thus be seen that this frequency responsiveness of the receiver 6 is constant during the periods MN and QR as the cut-out ABC is entering and leaving the stator 16, and the receiver 6 is momentarily a fix-tuned receiver.

This variation of tuning with time as shown in Fig. 2 (D) produces an output from the receiver (for signals distributed through the spectrum). This output is applied to the vertical deflection plates of the oscilloscope 14, causing the picture of Fig. 4 to appear, assuming a sweep frequency of conventional saw-tooth pattern synchronized with the scanning condenser in the usual manner. The normal resonance curves will appear in the sweep FG except at HI, where a small section of the time-wave shape corresponding to the signal of the frequency to which the receiver 6 is momentarily tuned, will appear. By careful adjustment of the tuning condenser C_2 in parallel with the scanning condenser C_1 , precise tuning of the cut-out portion HI will be obtained.

The above description has assumed the usual saw-tooth wave pattern applied to the horizontal plates of the oscilloscope 14. If, however, the horizontal sweep voltage E_h of Fig. 2 (A) is employed in conjunction with a vertical deflection voltage, Fig. 2 (B) mixed with the received signals, which have been scanned by the condenser C_1 of Fig. 1 to produce the tuning variation of Fig. 2 (D), then the picture appearing on the oscilloscope screen will be as in Fig. 5, for reasons which will now be explained.

It will be noted that curve portion LP of Fig. 2 (D) is similar in form to curve portion L'P' of Fig. 2 (A) and that they occur during the same time interval. During sweep FJ (Fig. 5) produced on the oscilloscope screen by the increase in sweep voltage L'M', the frequencies LM (received during this time interval) produce the usual picture as shown. Now, however, during period M'N' no sweep occurs, and in addition during this period a single frequency is being received due to tread MN in Fig. 2 (D). Since no horizontal deflection occurs during this period, portion HI (formed as a result of the continuous sweep in Fig. 4) will close up into line JK of Fig. 5, and will be brighter than the normal resonance curves. Voltage increase N'P' now completes the sweep of the beam across JG, and pictures the curve portion NP of Fig. 2 (D). Thus a pause is produced in sweep FG at point J in Fig. 5, corresponding in duration to the time interval M'N'.

As the condenser unmeshes, portion PQ of Fig. 2 (D) is not shown on the oscilloscope screen because there is no sweep voltage applied during this time interval, as shown in wave portion P'Q' of Fig. 2 (A). When point Q is reached, or Q' in Fig. 2 (A), the steady frequency QR is being traced on the screen by the increase in sweep

voltage Q'R', flat portion of dotted line P'Z' equals QR of Fig. 2 (D), the latter reaching the same maximum as sweep L'P' and thus giving as long a sweep in a much shorter interval. How this wave, Fig. 2 (A), is produced will herein-after be explained. Portion RZ is not shown on the screen because during this time the sweep voltage is a minimum, as can again be seen from wave portion R'Z' of Fig. 2 (A). In other words, of the portion PZ of Fig. 2 (D), only the horizontal portion QR is shown on the oscilloscope screen, and furthermore this portion is swept across the screen to give a full-size picture of the steady frequency to which the receiver 6 is momentarily tuned.

Coming now to wave (B) of Fig. 2, it was hereinbefore stated that this wave was a vertical deflection voltage mixed with the received and scanned signals. During time YU this voltage is steadily positive and the sweep FG is across the upper portion of the screen. However, from U to S the application of a constant negative voltage causes sweep F'G' (the picture in Fig. 5 of steady frequency QR) to operate on the lower portion of the screen. Thus the complete picture of Fig. 5 is obtained, and proper adjustment of the tuning condenser C_2 in parallel with the scanning condenser C_1 will spread any desired frequency of the received band across the lower portion of the screen.

Wave (C) of Fig. 2 is applied to the grid of the oscilloscope 14 in the conventional manner to blank the beam except when wanted. The periods of blanking can be easily seen by comparison of the corresponding time intervals. Thus the beam is effective during sweep periods L'M'N'P' and Q'R', and blanked during the remaining time. This eliminates the return trace and improves the sharpness of the picture obtained.

The output of the receiver 6 resulting from operation of the condenser C_1 , is superimposed on vertical deflection voltage (B), the wave controlling the position of the picture on the screen. Horizontal deflection wave (A), the sweep voltage, is applied to the horizontal deflection plates. Blanking wave (C) is applied to the control grid of the oscilloscope 14. The resulting oscilloscope picture is shown in Fig. 5. Curve (D) should be understood as not representing a voltage wave in the manner of waves (A), (B) and (C), but as merely showing in graphical form the frequency responsiveness of the receiver 6. In other words the receiver 6 will be receptive at any particular time to the frequency shown by the curve (D), and if a signal of that frequency appears at that instant it will be received and pictured on the oscilloscope screen.

To produce the horizontal deflection wave of Fig. 2 (A) the circuit of Fig. 1 is employed. A rotating switch S_1 has two conducting segments d_4 and d_5 positioned as shown. This switch is connected in parallel with the condenser C_3 . The two triodes V_1 and V_2 are controlled by voltages from wave spacers and shapers 10 and 9 respectively applied to their grids to control the bias thereof. As hereinbefore stated the switch S_1 rotates synchronously with the scanning condenser C_1 .

Referring now to the wave form (A) of Fig. 2 which is produced by the circuit of Fig. 1, it will be seen that to produce the portion L'M' the brush of switch S_1 is on insulating segment d_1 . The grid of V_1 is negative and no current flows through V_1 . The grid of V_2 is positive, and current flows through V_2 , but sufficient current

reaches C_3 to build up a potential thereon (and on the horizontal plates of the oscilloscope 14) corresponding to voltage $L'M'$.

Over insulating portion d_2 of S_1 , V_2 continues to pass current, but V_1 is now operative to hold the voltage constant across C_3 . This produces the horizontal tread $M'N'$. Over d_3 the condition is similar to d_1 , and thus the wave form $L'M'N'P'$ is created.

Upon reaching the intersection d_3-d_4 , the brush of rotating switch S_1 contacts the conducting segment d_4 and the condenser C_3 immediately discharges to give the return sweep which is blanked by wave C of Fig. 2. No further potential is built up across the condenser C_3 until d_5 is reached. (V_1 is inoperative during the entire time except while the brush of switch S_1 is on portion d_2 .)

When d_5 is reached, V_2 is suddenly keyed out. All the current now reaches C_3 , and a very rapid build up (or rapid sweep $F'G'$) is obtained. This build-up will reach an amplitude R' as shown in Fig. 2 (A) equal to P' . Upon contacting d_6 the condenser C_3 again discharges. The desired wave pattern (A) is thus created. It might be mentioned that V_1 has for its function the production of the horizontal tread $M'N'$, and V_1 is only operative during this interval $M'N'$ (d_2). The function of V_2 is to reduce the voltage applied to C_3 during all times except $Q'R'$ (d_5). V_1 is inoperative except during d_2 . V_2 is operative except during d_5 . R_3 and R_4 should preferably be low compared to R_1 and R_2 so that the time constant is not appreciably affected by the action of V_2 .

While I have shown and described the invention as a monitoring system, it is contemplated that the apparatus disclosed may be employed with a transmitting arrangement to result in improved jamming of an enemy station operating on a particular frequency. By alternate blocking of the receiver and transmitter in a manner described in my co-pending application 471,237, filed January 4, 1943, the two indications may be made to appear on the oscilloscope screen, and they may be separated into waves having opposite slopes on the lower portion of the screen by properly attenuating the low frequency response of the audio output stage feeding the vertical deflection plates of the oscilloscope. Since the received wave picture and the transmitted wave picture will thus be in close proximity on the screen, the frequency of the jamming transmitter may be easily adjusted to result in similar wave patterns and thus more efficient jamming.

While I have described above the principles of my invention in connection with specific apparatus, it is to be clearly understood that this description is made only by way of example and not as a limitation on the scope of my invention as set forth in the objects of my invention and the accompanying claims.

I claim:

1. A radio receiver system comprising a tunable radio receiver, means for periodically maintaining said receiver receptive to substantially a single frequency for a predetermined period of time, means for periodically continuously varying alternately with the said maintaining means the tuning of said receiver over a predetermined frequency band embracing the said single frequency, an oscilloscope in the output of said receiver, scanning means for the oscilloscope, a resistance condenser circuit connected to said scanning means, a source of power for the re-

sistance condenser circuit, means for charging and discharging said resistance condenser circuit to derive therefrom a predetermined voltage wave for application to said scanning means, and 5 means for synchronously controlling said tuning varying means, said maintaining means, and said mechanically controlled means.

2. A radio receiver system according to claim 1, further comprising means for manually controlling the selection of the band over which the said tuning varying means is effective.

3. In a radio receiver system a vacuum tube circuit including a condenser, two triodes, means feeding the outputs of said triodes to said condenser, control means for selectively biasing the grids of said triodes to control the output thereof, a switch, means for controlling said switch to periodically short circuit said condenser, means for synchronizing the operation of said grid biasing control means and said switching means, and scanning tuning means in said receiver circuit, an oscilloscope, means delivering the output of said receiver circuit to one set of deflection plates of the oscilloscope, means delivering the output of said condenser to the other set of deflection plates of the oscilloscope, and means for extending the control of the said synchronizing means to include the said scanning means.

4. A radio receiving system comprising a radio receiver, a mechanically-rotated scanning condenser in said receiver, said scanning condenser having a stator combined with a rotor plate formed of two segments of less than 90° each, separated on one side by a cut-out portion ex-

35 tending over an angle of approximately 180° and on the other side by a cut-out portion extending over an angle of substantially less than 180° , so that rotation of the rotor will cause the capacity

40 of said scanning condenser, and consequently the frequency received by said radio receiver, to remain substantially constant during the time that both cut-out portions are simultaneously respectively entering and leaving the stator, an oscillo- 45 scope, means for delivering the output of said receiver to one set of deflection plates of the oscilloscope, a resistance condenser circuit connected to a second set of deflection plates of the oscilloscope, a source of power for the resistance condenser circuit, mechanically controlled switching means for controlling the charging and discharging of the condenser of said resistance condenser circuit to derive therefrom a voltage wave for application to the said second set of deflection

55 plates of the oscilloscope, said switching means comprising a fixed contact and a rotating contact of substantially circular form and having two spaced-apart conducting segments of less than 90° each, separated on one side by an insulating

60 segment of approximately 180° and on the other side by an insulating segment of substantially less than 180° , so that rotation of said rotating contact will permit the condenser of said resist- 65 ance condenser circuit to charge only during the

intervals that the said insulating segments of said rotating contact are in contact with said fixed contact, and means for synchronizing the operation of the said mechanically-rotated scanning condenser and the said mechanically-controlled switching means result in a correlation of the voltages delivered to the two sets of plates of the oscilloscope.

5. A radio receiving system according to claim 4, further comprising two vacuum tubes in said resistance condenser circuit, means for operating

the said tubes to control the charging of said condenser, and means for synchronizing the operation of the said tube operating means with the said mechanically rotated scanning condenser and the said mechanically controlled switching means.

6. The combination according to claim 4 in which the contacting areas of said conducting segments each extends over an angle equal to the angle of each of said rotor plate segments, and the insulating segments respectively extend over angles equal to the angles separating the segments of the rotor.
